DESIGN FOR A TOOTHBRUSH

Kenneth Harris and Otto A. May, Chicago, Ill.

Application July 30, 1947, Serial No. 140,619

Term of patent 7 years

(Cl. D9—2)

To all whom it may concern:

Be it known that we, Kenneth Harris and Otto A. May, both citizens of the United States, residing at Chicago, in the county of Cook and State of Illinois, have invented a new, original, and ornamental Design for Toothbrush, of which the following is a specification, reference being had to the accompanying drawing, forming part thereof.

In the drawing:

Figure 1 is a top plan view of a toothbrush, embodying our new design;

Figure 2 is a side elevational view of the toothbrush; and

Figure 3 is a front elevational view of the toothbrush.

We claim:

The ornamental design for a toothbrush, as shown.

KENNETH HARRIS.
OTTO A. MAY.
